CLEANING BRUSH

Paul H. Durup, Wollaston, Mass., assignor to
 Art-O-Graphic Printing Company, Inc., Boston,
 Mass., a corporation of Massachusetts

Application June 2, 1938, Serial No. 211,348

4 Claims. (Cl. 271—12)

This invention relates to a cleaning mechanism for an offset printing machine.

With stacks of sheets to be printed, and in particular envelopes, fine particles of dirt or other foreign matter tend to collect on the sheet surfaces, which are readily picked up by the transfer blanket of an offset printing machine and upon continued occurrence, various undesirable effects in the printing result, as for instance where the particles adhere to the roll, spots in the printed area become apparent, and such foreign material as may eventually be carried over to the printing roll and doctor blade, may collect and present unsightly lines or smears on the subject matter. This difficulty is particularly present in the printing of envelopes. One reason is that particles of dried glue are present on the backs of envelopes where their edges are secured together. These particles are very fine and require a positive cleaning action to be removed and prevented from collecting on the blanket. The following subject matter constitutes means for obviating such difficulties.

Among the objects of the invention are means to provide cleaning of the surface of subject matter such as envelopes, cards, and similar sheets, during the period in which said subject matter is passing from a stacked position to the printing members; to combine positive conveying action of the subject matter with such cleaning; to direct dirt or other foreign matter removed from the sheets away from the printing members; and generally to present a simple, cheap, and efficient cleaning mechanism suitable for the purpose described and particularly suited to treatment of envelopes printed at high speeds.

The invention consists in means for subjecting the surfaces of subject matter to friction, brushing, suction, blowing and the like.

In the drawing illustrating my invention:

Figure 1 is a side elevation of my improved cleaning mechanism shown in association with a conveyor frame and stack holder for subject matter to be printed;

Fig. 2 is a cross section taken on the line 2—2 of Fig. 1;

Fig. 3 is a detailed fragmentary plan view of modified guiding means for properly insuring passage of subject matter to be printed along the conveyor belts; and

Fig. 4 is a detailed fragmentary view in partial cross section further illustrating the modification shown in Fig. 3.

In the drawing, 10 indicates a frame in which are located conveyor belts 11 adapted to receive

sheets of subject matter removed from a stack 12, in a stack holder 12—a, by suction means 13 as described and claimed in my co-pending application Ser. No. 168,853, filed October 14, 1937. The conveyor belts carry the sheets of subject matter under a guiding roll 14, and then through the cleaning mechanism illustrated at the left-hand side of Fig. 1, and finally to offset printing means, not shown, occurring at a point beyond the cleaning mechanism. 10

The sheets of subject matter coming from the stack 12 are particularly illustrative of envelopes but are intended also to be generally exemplary of various types of sheets as cards, blotters and the like. 15

15 denotes a shaft having its ends journaled in plate members 16 and 17 mounted on the frame 10 ahead of the guiding roller 14. Solidly fixed on shaft 15 is a brush 18 which may comprise any suitable bristle construction such as wire, hair, 20 and the like, and may be of varying degrees of stiffness as required by the sheet surface to be cleaned. The brush 18 is also intended to be illustrative of various other types of cleaning means suitable for removing glue and other foreign substances from sheets of subject matter to be printed. For example, I may prefer to utilize friction cleaning rolls or suction devices capable of effecting the desired cleaning action and any of the devices referred to are not required to be limited to the exact point of location shown in the drawing but may occur at any suitable point between the release of the subject matter by the suction member 13 and its entering the printing members. 25 30 35

As indicated in Figs. 1 and 2, brush 18 is driven in a counter clockwise direction by some suitable means as for instance a pulley 19 and belt 20. The other end of belt 20 may be associated with some rotating part of the conveyor mechanism as 40 the roll 21 for conveyor belts 11.

To more properly present an envelope 25 to the cleaning action of the brush 18 and to continue its advance along the belts at high speeds and against the action of the brush, it may be 45 desirable to provide some contacting surface other than the conveyor belts 11 and for such a purpose I have located rollers 22 and 23 on a shaft 24 mounted through frame 10. As may be noted in Figs. 1 and 2, the rolls occur directly under the brush 18 and somewhat centrally thereof. The rolls 22 and 23 are also driven in a counter clockwise direction by some convenient means as for instance belt 26 passing over roll 21 already referred to. In addition to the rolls, 50 55

there has been provided a supporting plate 27 which is located just under the belts 11 and extends in front and in back of the brush and is cut out to permit peripheral portions of rolls 22 and 23 to extend upwardly therethrough.

5 A further advantage in the plate 27 relates to the operation of the machine. As previously stated the subject matter of the present invention is being used in connection with high speed 10 printing operations and in particular with high speed printing on the backs of envelopes where the use of grippers is not relied on. It is in the 15 nature of envelopes which have several glued together edges and one free glued flap that curling and upturning of edges will be present. The 20 action of the particular cleaning means here illustrated, the brush 18, may tend to further develop upturning of edges with the result that clogging and break-down of operation takes 25 place. To insure against such possible action of the envelopes or other subject matter some means of maintaining the envelope in a flat state is desirable and with whatever means may be employed the plate 27 cooperates to overcome such difficulty.

As one example of the means referred to, I have shown in Fig. 1 resilient spring members 28 having one end fixed to and supported by a bar 29 occurring transversely of the plates 16 and 30 17. The other ends may be curved around to a point just in front of the brush 18 and tend to maintain the front edge of an envelope in a flat state against the plate 27.

In Figs. 3 and 4 I have shown a modification 35 of means for maintaining subject matter flatly against the plate 27. This modification comprises essentially a plurality of wire members 30, of some suitable stiffness, as for instance piano wire, which are adapted to run through and beyond the brush 18 without to any appreciable extent interfering with the cleaning action of the brush. Any suitable means of support may be resorted to as for example a bar 31 in which are received a plurality of keys 32 threadably engaged therewith and having the ends of the wire members wound around in such manner that these ends may be tightened or released as desired. The other ends of the wire members 30 have been secured in a rod 33 having central 45 slotted openings 34 for receiving the ends and these ends are fixed by means of set screws 35 as illustrated.

To further maintain subject matter in a flat state against the drag of the brush 18 as it passes 55 over the rear edge of the subject matter, there has been provided floating rollers 36 having elongated slots 37 for being adjustably mounted on a shaft 38. The shaft 38 is received in the members 16 and 17 in elongated slots 39 and has been further provided with bent spring clips 40 which function to resiliently maintain the shaft and rolls in a depressed position.

In effecting the cleaning by the mechanism disclosed there may occur particles of dust and dirt in the air which if allowed to contact the transfer blanket of the machine would be very undesirable. To guard against such a condition, there may be provided means of blowing such particles in a direction away from the transfer blanket and as one example of such means there is illustrated a bracket 42 carrying a tube 41 which is formed with openings for emitting blasts of compressed air from a source not shown, in the direction indicated in the drawing.

It will be seen that there is provided a simple, cheap and efficient cleaning mechanism which adequately removes foreign matter and in particular glue on envelopes and this result is effected without lowering the rate of speed of operation and without creating clogging difficulties.

Having thus described my invention, what I claim is:

1. A cleaning mechanism for envelopes, cards and like materials to be printed comprising in combination a conveyor, a rotating body in said conveyor, supporting means for presenting the surface of said subject matter to the rotating body, means for maintaining the subject matter flatly against the said supporting means and driving means for facilitating advancement of said subject matter along said conveyor.

2. A cleaning mechanism for envelopes, cards and like materials to be printed comprising in combination a conveyor, a brush mounted in said conveyor adapted to contact the surface of said subject matter to be printed and means comprising a plurality of wires extending through said brush for maintaining said subject matter flatly against the conveyor.

3. A cleaning mechanism for envelopes, cards, and like materials comprising in combination a conveyor, a rotating brush transversely disposed in the conveyor for contacting the surface of said subject matter to be printed, a base in the conveyor for presenting subject matter against said brush, means for maintaining said subject matter flatly against said base, and driving rollers located below said brush and having a peripheral portion extending through said base to contact the subject matter passing between the brush and the said peripheral surface.

4. A cleaning mechanism for a printing machine comprising a conveyor for advancing subject matter to be printed in said machine, a base located adjacent said conveyor, a depression member for maintaining said subject matter flatly against said base while advancing on the conveyor, a brush rotating in a direction opposite to the movement of the conveyor, and rollers for maintaining the front end of said subject matter flat while the brush is in contact with the rear end.

PAUL H. DURUP.
